Design No 763.

*R. Clemons' Design for Carter's
Egg Cup Stand.*

Assigned to R. Clemons & Sons.

Patented Feb. 12th 1856.

Res. 763

R. Gleason, Jr. of Dorchester, Mass.

Assignor to

R. Gleason & Sons, of same place
Letters Patent No. 763, Dated Feb. 12. 1856.

The schedule referred to in these Letters Patent, and making part of the same.

To all whom it may concern.

Be it known that I, R. Gleason, Jr. of Dorchester, in the County of Norfolk, & State of Massachusetts, have invented or produced a new & ornamental design for a bottle caster & egg cup stand; & I do hereby declare that the following is a full, clear, & exact description of the same, reference being had to the annexed drawings, making a part of this specification, in which

Fig. 1. is an elevation of a caster & cup stand showing my design.

Fig. 2. is a top view of do.

Fig. 3. is a top view of the base.

A. represents the base of the caster & cup stand, the base being of flaring or bell shape, & having ornaments B. B', B". B", upon its sides. The ornament B. is composed of a rose (a) surrounded by leaves (b) & having a scroll (c) at each side, as plainly shown in figs 1 & 3. The ornament B' is composed of two roses (a') (a') & leaves (b') as shown in fig 3. The ornament B" is composed of flowers (c') surrounded by leaves (d') & having a scroll (e') at each side, as shown in fig 3. The ornament B''' is composed of two flowers (f') (f'), & leaves (g') also shown in fig 3.

C. represents the sockets or holders in which the bottles are placed. The sockets are of semi-cylindrical form & their upper & lower edges have scrolls (d) upon them, see fig 1. The outer sides of the sockets have ornaments D. upon them, composed each of two scrolls (e) (e) connected at their upper & lower ends by

shells (f). Rose leaves (g) branch out from one scroll (e) a rose (m) being at the end, f leaves (i) branch out from the opposite scroll (n) bearing a flower (j) resembling a pink at their ends.

Between the sockets (C) circular plates E, are secured, said plates forming stands for the egg cups. These plates or stands have each a beaded rim (k) around them, as shown in fig 2. In each leaf or scroll l, is placed each side of the plates, at their junction with the sockets C. A scroll (C') formed as shown in fig 2, to receive spoons, is attached to the edge of each plate E.

F, represents the handle of the caster, & cup stand. The body of the handle is formed of leaves (m) branching or shooting from a stalk (o). If a human figure H, provided with a bow, is placed in an erect position on the handle.

What I claim as new & desire to secure by Letters Patent, is

The ornaments B, B', B", B", upon the sides of the base A; the scrolls (d) on the upper & lower edges of the sockets C; the ornaments D, upon the outer sides of the sockets, the beaded rims (k) of scrolls, C', on the plates E, of the figure H, of leaves (m) which form the main portion of the handle F, the whole being arranged & combined as described, to form an ornamental design for a bottle caster & egg cup stand.
